KNITTED LACE FABRIC AND ARTICLES

Gustav Gastrich, Wyomissing, Pa., assignor to
 Textile Machine Works, Wyomissing, Pa., a
 corporation of Pennsylvania

Application September 23, 1932, Serial No. 634,469

3 Claims. (Cl. 66—180)

This invention relates to novel knitted lace or open-work fabrics as well as articles of wearing apparel, such as hosiery, made therefrom; and to a new method of knitting the same with well known lace stitches, however, so that substantial enlargement of the openings forming the lace design is prevented when the thread of any of the opening-forming stitches is ruptured.

The use of knitted lace in the production of various articles of wearing apparel, particularly ladies' hosiery, is highly desirable because of the many ornamental designs and pleasing effects obtainable. However, owing to the delicate nature of the majority of the heretofore produced knitted lace, due directly to the ever-present liability of thread rupture of the lace forming stitches resulting in distortion or enlargement of the individual lace openings, these more or less costly articles have been frequently discarded long before being actually worn out. Such disadvantages have, in the past, materially restricted the use of various knitted lace articles, especially fine stockings, which are particularly subject to this condition.

In most of the heretofore produced lace fabrics, if the thread of any of the opening-producing stitches is ruptured, the lace opening immediately spreads or enlarges due to release and unravelling of the broken thread, thus irreparably distorting or destroying the design. This is due to the fact that the opening-forming stitches of these fabrics are so connected as to readily unravel, once they are ruptured.

The lace forming stitches are normally often under tension and, therefore, are more easily ruptured, and in stockings, increased tension is applied when stretched tightly upon the leg of the wearer. A broken thread in a lace stocking cannot ordinarily be caught up or the lace opening repaired in a suitable manner to satisfactorily restore the original design and appearance of the design unless the extent of the openings is limited.

Thread rupture of one or more of the lace forming stitches also tends to cause a walewise run in close-knit or other knitted areas adjacent the lace openings, and such a run may extend into an adjacent lace opening, thus not only affecting the lace opening in which the run started, but also affecting adjacent areas.

The term "lace fabric", as used herein, and as generally understood in the art, refers to a knitted fabric having therein an openwork ornamentation, or a fabric wholly or partly made up of ornamental opening-forming stitches, such as

transferred stitches, tuck stitches, drop stitches, or other open-work producing stitches, as distinguished from plain chain stitches.

While certain knitted lace fabrics have been produced by special stitches which are inherently impervious to unravelling in case of thread rupture, such stitches cannot be utilized in obtaining the same pleasing design effects produced by the various opening-forming stitches which are ordinarily subject to unravelling.

One object of my invention is to provide novel means in knitted lace fabrics whereby lace openings, formed by ordinarily raveling lace stitches, are made impervious to substantial enlargement or distortion when the thread of said stitches is ruptured.

Another object is to knit such fabrics by a new method whereby barrier stitches are combined with the usual lace forming or open-work producing stitches in novel manner; thereby enhancing the appearance and quality of the fabrics and the articles made therefrom.

A further object is to combine barrier stitches with the usual lace forming stitches in lace ornamented knitted fabrics and thereby provide run-proof knitted lace work fabric.

Another object is to provide lace fabrics having therein old and well known designs, however, in which the lace openings cannot spread or enlarge, as heretofore, in case a thread is ruptured in the surrounding lace-forming stitches.

Another object is to produce a lace fabric in which thread rupture of one of the lace forming or open-work producing stitches is prevented from spreading to, or causing a "runner" in, areas adjacent thereto.

Another object is to provide novel lace stockings having the above mentioned advantageous characteristics.

With these and other objects in view, which will become apparent from the following detailed description of several illustrative embodiments of my invention, shown in the accompanying drawings, the invention consists in the novel method of producing new and improved knitted fabrics and articles, as hereinafter more particularly pointed out in the claims.

Fig. 1 is a view, on an enlarged scale, of one combination of lace-forming stitches and barrier stitches in accordance with the invention;

Fig. 2 shows lace-forming stitches and barrier stitches in combination with plain knit courses;

Fig. 3 shows a modified arrangement of stitches which may be employed;

Fig. 4 shows a stocking composed substantially

entirely of lace made in accordance with my invention;

Fig. 5 illustrates a full-fashioned stocking having lace areas employing the stitches of Figs. 1, 5 2 or 3; and

Fig. 6 shows a stocking in accordance with the invention having lace clockwork and a lace area in the welt.

In knitting the stocking of Figs. 4 to 6 the welt 10 portion 8 is knitted first, as usual, and the leg 9 is begun at the welt and knitted toward the foot portion 10. Therefore, in Figs. 1, 2 and 3 which are enlarged diagrammatic views of 15 patches of fabric from the stockings illustrated, the order of knitting the courses is from the top course downward.

Referring to Fig. 1, the lace fabric comprises 20 openings formed by courses 10 and 13 having barrier stitches interlocked with open-work producing stitches, and separated by two courses 11 and 12, or 14 and 15, having other open-work producing stitches therein, the open-work producing stitches of each opening extending into four successive courses and into four adjacent wales 25 16 to 19. Courses 10 consist of alternate plain loops 20 and barrier stitches in the form of spread interlocking loops 21. In producing the barrier stitches 21 of each course 10 or 13, I first 30 form a course of plain loops and then before the same are cast off their needles, certain loops, preferably alternate loops, as shown, are spread from the wales 17 and 19 in which they originate to adjacent wales 18 and 16, respectively, in the same course, and in the adjacent wales the bight 35 portion 21a of each spread loop engages under the needle loop and over the associated sinker or divider loop so that the portion 21a will be held between a needle wale loop and a sinker wale loop. The barrier stitches just described may be 40 knit either by hand or by machine, and may be automatically produced on full fashioned knitting machines of the well known "Reading" type when used with the loop spreading mechanism described and claimed in my copending application 45 Serial No. 623,206 filed July 18, 1932 for Knitting machine and method for the production of non-run fabric.

In course 11, plain loops are first formed and, 50 in order to produce the lace opening, selected loops 22 and 23 in wales 17 and 18, respectively, are transferred to the adjacent needles; the loops in wales 18 are transferred to the right into wales 19, and those in wales 17 are transferred to the left into wales 16, to form an opening of desired width. In course 12, the loops 24 which ordinarily would comprise loops in wales 17 and 18 55 are transferred to the right into wales 19 to continue the lace opening in a manner well known in the art.

60 In the succeeding course 13, plain loops are first formed, the sinker loops 25 engaging with the thread of loops 24 to complete the lace openings. As in course 10, alternate loops are spread into adjacent wales to form barrier stitches 21, except that they are spread from wales 16 and 18 65 into wales 17 and 19, respectively, and are therefore staggered with respect to the barrier stitches in course 10, each of the barrier stitches preventing a run in the wale from which it is spread.

In the succeeding rows of lace openings, the same formation of stitches obtains, the openings of each row being preferably, although not necessarily, offset or staggered with respect to 75 those in the preceding row. In course 14 the

transferred loops 22 and 23 are interlocked with adjacent barrier stitches 21. In course 15 the loops 24 are transferred to the right, as in course 12, to continue the lace opening. In course 10 adjacent course 15, the thread of each loop 24 is 5 locked with the associated sinker loop 25a of the barrier stitches.

Due to the interlocking engagement of the barrier stitches 21 with the transferred loops 22, 23 and 24, any thread rupture occurring is prevented from forming a run, or from substantially distorting the lace design. For example, thread rupture of the open-work producing or transferred stitches will not cause substantial spreading or enlargement of the lace opening 15 because the transferred stitches are gripped or interlocked at various points with the barrier stitches. Since ravelling of any of the lace forming stitches is substantially prevented, ravelling or loosening of the adjacent stitches is prevented, 20 or is confined to the immediate vicinity of the rupture, thus preventing distortion of the lace design beyond satisfactory repair. Also, any thread rupture occurring is mostly likely to occur in one of the lace forming stitches, and therefore possibility of a run is substantially prevented by locking the lace forming stitches in the manner disclosed.

Fig. 2 shows an arrangement in which courses 26 of plain chain stitches form plain-knit areas 30 between adjacent rows of the lace openings. Although two plain knit courses only are shown, it will be understood that any desired number of such courses may be interposed, or that the courses 26 may comprise or consist of stitches 35 other than plain chain stitches. In any case, a run due to thread rupture in the plain or other knitted areas is stopped or is limited by the barrier stitches 21 in courses 10 and 13, so that thread rupture occurring in the plain knit areas 40 will not distort or destroy the lace design.

Fig. 3 shows another arrangement in which the lace forming stitches are combined with barrier stitches 21 and also with a modified form of barrier stitch 27. It will be seen that in courses 45 28, the loops 27 originating in wales 34 and 36 are extended or spread into the adjacent wales 37 and 35, respectively, and also into the succeeding course 29, so that the loops which would ordinarily form needle loops in the course 28 are 50 carried into the succeeding course 29 and displaced transversely in that course, thus forming part of the wales 35 or 31, as the case may be. In these wales the bight or spread portion 27a of each loop 27 engages under a needle loop and 55 over the associated sinker or divider loops as the case may be, with the lace forming stitches 22 and 23. In course 30 the stitches 22 and 23 are transferred to the left and right, respectively, to 60 continue the lace opening.

In course 31 the loops 38 which ordinarily would form loops in wales 37 are transferred to the left into wales 36 and there interlock with sinker loops 39 associated with barrier stitches 21. Barrier stitches 21 are also provided in course 31, and are spread from wales 35 into wales 34, thus locking wales 35 and coacting with barrier stitches 27 and the lace forming stitches 22, 23 and 38 to prevent runs in the lace 70 areas. In courses 32 and 33 the barrier stitches 21 are spread into adjacent wales and also into succeeding courses in the manner of these stitches in courses 28 and 29, except that the barrier stitches in courses 32 and 33 interlock 75

with the lace forming stitches in the course from which they are spread by means of their associated sinker or divider loops.

Fig. 4 shows a stocking in which the leg portion 9 is composed substantially entirely of lace, and employing the stitches of Fig. 1; due to the barrier stitches interlocking with the lace forming stitches the stocking is rugged and substantially run-proof, notwithstanding the sheer nature of the lace of which it is composed.

In Fig. 5 the stocking has an area 40 comprising plain courses, such as 26 in Fig. 2, with bands 41 of lace-forming stitches combined with barrier stitches in the manner above disclosed. It will be understood, however, that various courses in the area 40 may comprise barrier courses to limit runs therein, or that the entire area 40 may comprise barrier stitches so arranged as to make the area substantially run proof.

Fig. 6 shows a lace band 42 in the welt, and also lace clockwork 43, in which the lace-forming stitches are combined with barrier stitches of the type shown in Fig. 1, 2 or 3. As in the stocking of Fig. 5, various of the courses in the area 40 may be barrier courses to limit or substantially prevent runs therein.

I am aware that spread loops of the type disclosed have been employed to produce an ornamental effect in a fabric, but I believe myself to be the first to combine or interlock lace-forming or open-work producing stitches with barrier stitches in the manner and for the purpose disclosed herein.

Of course, various other forms of barrier stitches known in the art may be employed to interlock with the lace forming stitches generally in the manner above described, and various other types of lace-forming stitches other than those shown may be used to engage or interlock with the barrier stitches shown, or with other forms of barrier stitches for the purpose, and generally in the manner above described, and it will be obvious to those skilled in the art that various specifically different arrangements may

also be employed to obtain substantially the advantages of the invention.

The term "spread", as used in the specification and claims, defines a locking loop having one or both legs remaining in its wale of origin and a bight thereof extended to, and knit with, a loop of an adjacent wale in the same or a succeeding course.

I claim:

1. A knitted stocking having a continuously knit ornamental area comprising a series of regularly spaced rows of lace-opening defining loops including one or more loops which when ruptured will permit substantial enlargement of the openings defined by said loops, and a series of rows of special loops interknit with and alternately spaced with said first rows, the construction of said special loops being such as to ensnare said first loops to prevent substantial enlargement of the lace openings defined thereby upon rupture of the yarn of said first loops.

2. A continuously knit ornamental lace fabric having successive courses composed of loops defining spaced ornamental lace openings including one or more loops which when ruptured will permit substantial enlargement of the openings defined by said loops, and other loops adjacent the upper and lower edges of said openings interknit with and adapted to ensnare the yarn of said first loops to prevent substantial enlargement of the lace openings defined thereby upon rupture of the yarn of said first loops.

3. A continuously knit stocking fabric comprising courses having ornamental openings each defined by a plurality of loops including one or more loops which when ruptured will permit substantial enlargement of the openings defined by said loops, and a plurality of yarn-ensnaring loops adjacent to the upper and lower edges of said openings adapted to stop unraveling movement of the yarn when yarn rupture occurs in the opening-defining loops, thereby limiting wale-wise extension of the ornamental openings.

GUSTAV GASTRICH.
